ABSTRACT: A finishing wood covering laid over a subfloor and comprising a plurality of finishing wood panels secured over the subfloor in edge abutting relationship with each other, each panel being cut out along the abutting edges to define a recess, at the top, having a horizontal ledge and an inclined inner lateral wall, and being further cut out at the bottom along the abutting edges to form a horizontal groove. The recess and the groove of a panel define therebetween an overhanging tongue that extends fully around the panel, the top recesses of abutting panels thus having a dovetail configuration. A plurality of fastening clips are mounted on the tongues of abutting panels to hold them together and fasten them to the floor. Each clip is formed of an upstanding web disposed between the facing ends of the tongues of the corresponding abutting panels and lateral prongs projecting from the top and bottom of the upstanding web to overlie the horizontal ledges of the tongues and to be received in the bottom grooves of the corresponding abutting panels, respectively. There is for each clip, two spaced top prongs extending in one direction from the web and a further top prong extending in opposite direction between the first two prongs. There is also provided, for each clip, two spaced bottom prongs that extend in the said opposite direction while a further bottom prong extends in the one direction aforesaid between the first bottom prongs. The panels are secured to the subframe by means of a nail, for each clip, driven in the space between the first two top prongs, driven through the tongue, through the further bottom prong and into the subfloor. Finally, filler wood strips of dovetail cross section are set in the said recesses defined between the abutting panels.

WOOD FLOOR FINISHING CONSTRUCTION

The present invention relates to the construction of wooden floor surfaces and particularly to a finishing layer of wood on a prepared unfinished subfloor surface.

It is commonly known to finish wooden floors by the addition over the unfinished subfloor surface of a layer of hardwood in the form of narrow planks. It is also generally accepted that composite sheetlike boards of wood are not a suitable material for the finishing of floors. This hitherto nonexistent utility for sheetlike wood boards or panels such as plywood and various forms of so-called particle boards, stems mostly from the fact that regardless of the skill that goes into producing the joints between consecutive sheets, such joints always remain apparent and unsightly unless extreme precautions are observed to ensure a perfect match or continuity of the wood grain between consecutive sheets.

The relatively large dimensions of plywood or particle boards or panels are such that they necessitate being nailed down or otherwise secured at positions intermediate between the edges thereof and the nails or other fastening means used for this purpose cannot easily be rendered non apparent.

The present invention proposes a new form of sheetlike boards or panels along with fastening edge clips and which are intended for use in constructing finished wood floors and do not present any of the aforementioned disadvantages and furthermore present advantages of its own; one of these advantages having to do with the relatively great rapidity with which the finishing of floors in accordance with the present invention can be achieved.

More specifically, the invention proposes a finishing wood covering laid over a subfloor, said covering comprising: a plurality of finishing wood panels secured over said subfloor in edge abutting relationship with one another; each of said panels being cut out along the abutting edges thereof to define a continuous recess at the top, having a horizontal ledge and an inclined inner lateral wall, each panel being further cut out at the bottom along said edges to form a continuous horizontal groove; the recess and the groove of a panel defining therebetween a continuous overhanging tongue extending fully around said panel, the top recesses of abutting panels thus having a dovetail configuration; a plurality of fastening clips mounted on tongues of abutting panels; each of said clips being formed of an upstanding web disposed between the facing ends of the tongues of corresponding abutting panels, and lateral prongs projecting from the top and bottom of said upstanding webs to overlie the horizontal ledges of said tongues and to be received in said bottom grooves of the corresponding abutting panels, respectively; there being for each clip two spaced top prongs extending in one direction from said web and a further top prong extending in opposite direction between the first two prongs; there also being for each clip two spaced bottom prongs extending in said opposite direction and a further bottom prong extending in said one direction between said first bottom prongs; a nail in said space, of each clip, between the two first top prongs, said nail being driven through said tongue, through said further bottom prong and into said subfloor, and filler wooden strips of dovetail cross section in said recesses defined between abutting panels.

In the accompanying drawing:

FIG. 1 is a perspective view of a floor corner in accordance with the present invention and showing a partially installed sheet board;

FIG. 2 is an exploded fractional perspective view showing how an assembly of adjacent and consecutive boards is realized in accordance with the invention;

FIG. 3 is a sectional view taken on line 3-3 of FIG. 1; and

FIG. 4 is a sectional view taken on line 4-4 of FIG. 2.

It is observed that in constructing floors in accordance with the invention sheets or panels 1 of laminated wood or of particle board are used; each sheet 1 presenting a number of 75

square or rectangular surfaces 2 which are defined by a series of grooves 3 and 4 of rectangular cross section which have depth which slightly exceeds the thickness of a filler strip 5 to be received therein. Once it has been properly positioned any board 1 is secured into place by means of nails 6 or similar fasteners which are driven therethrough and into the underlying subfloor structure; nails 6 are driven through the sheets 1 only at spaced apart positions along the bottom surfaces of the grooves 3 and 4, the head of each nail projecting over the surface of the bottom of the groove in each case.

The filler strips 5 are thereafter inserted in grooves 3 and 4 and securely fastened therein by means of an appropriate glue, cement or bedding compound. The thickness of each strip 5 is such that, as it rests over the heads of the nails 6, the top surface thereof lies in the plane of the surface of the sheet 1.

Peripherally of each sheet 1, there is a groove 10 the width of which, measured in the plane of the top surface of the sheet, is less than half the width of any groove 3 or 4. The upright wall 11 of groove 10 is sloped inwardly so that when adjacent sheets 1 are brought together the respective grooves 10 combine to form a track of dovetail cross section. Also peripherally of each sheet 1 but at the underside thereof there is also a shallow groove 12 the depth of which is equal to the thickness of the metal used for a sheet metal edging clip 13.

With particular reference to FIG. 4, edging clips 13 are used for interconnecting the abutting edges of adjacent sheets 1 and as a means for preventing any up or down displacement of the edge of one sheet relative to the edge of the other and vice versa.

The clip 13 is preferably made of sheet metal such as galvanized steel and consists of a double-ended three-pronged fork in which there is a transverse alternation of prongs 15 and 16 which are disposed according to two spaced apart horizontal planes corresponding to the bottom surfaces 17 and 18 respectively of the peripheral grooves 10 and 12.

In the process of laying out a finished floor according to the invention, each sheet is completely nailed down such as by means of nails 6 and 6' before any other sheet is brought to adjoin. The nails 6' are used to fasten down the marginal portion of the sheet 1 and are preferably driven at positions along the bottom of the groove 10 where they will be adjacent to one of the prongs 15 and overlie and puncture through one of the underlying prongs 16.

Once any sheet 1 has been completely fastened down by means of nails 6 and 6' and clips 13 have been positioned and simultaneously secured by nails 6' at spaced intervals along the free edges thereof, some strips 20 are positioned into the groove 10, (i.e. resting over the heads of nails 6' and the prongs 15) prior to bringing any adjacent sheet 1 into position with the edge thereof within the grip of the prongs 15 and 16 of the free ends of the clips 13. It is seen therefore that of the abutting edges of any two adjacent sheets 1 only one is fastened down by means of nails 6', the other being secured or held down by means of clip 13 only.

It must be understood that the filler strip 20 has a dovetail profile whereby it becomes locked in position when adjacent sheets 1 are brought together; the width of the strip 20 at the top would normally be equal to the width of any filler strip 5. Additionally, it is recommended that in order to be more securely fastened the strip 20 should be properly bedded by means of glue, cement or other suitable bedding compound.

The embodiment of the invention hereinbefore described may be observed to produce a checkered floor surface but it should be understood that, without departing from the invention, it would be possible to produce floor surfaces of various other designs, depending on the actual size and proportions of the basic sheetlike board unit. A preferred other design would result, for instance, from the use of sheetlike basic units of elongated rectangular configuration, having the same widths but unequal lengths; the resulting design would resemble that of a planked floor in which there is a narrow strip of wood separating every pair of longitudinally or transversely adjacent planks.

I claim:

1. A finishing wood covering laid over a subfloor, said covering comprising:
- a. a plurality of finishing wood panels secured over said subfloor in edge abutting relationship with one another;
  - b. each of said panels being cut out along the abutting edges thereof to define a continuous recess at the top having a horizontal ledge and an inclined inner lateral wall, each panel being further cut out at the bottom along said edges to form a continuous horizontal groove; the recess and groove of a panel defining therebetween an overhanging tongue having a facing end and extending fully around said panel, the recesses at the top of abutting panels thus having a dovetail cross section;
  - c. a plurality of fastening clips mounted on tongues of abutting panels;
  - d. each of said clips being formed of an upstanding web disposed between the facing ends of tongues of the corresponding abutting panels, and lateral prongs projecting from the top and the bottom of said upstanding web to

15

20

- overlie the horizontal ledge of said tongues and to be received in said bottom grooves of the corresponding panels respectively;
- e. there being for each clip two spaced top prongs extending in one direction from said web and a further top prong extending in opposite direction between the first two top prongs;
  - f. there also being for each clip two spaced bottom prongs extending in said opposite direction and a further bottom prong extending in said one direction between said first bottom prongs;
  - g. a nail in said space of each clip between the two first top prongs, said nail being driven through said tongue, through said further bottom prong and into said subfloor; and
  - h. filler wooden strips of dovetail cross section in said recesses defined between abutting panels.
